UNITED STATES PATENT OFFICE.

JOHN R. WILLIAMS, OF JOHNSTOWN, PENNSYLVANIA, ASSIGNOR TO
CAMBRIA IRON COMPANY.

MACHINE FOR TRIMMING HORSESHOE-BLANKS.

SPECIFICATION forming part of Letters Patent No. 225,255, dated March 9, 1880.

Application filed November 18, 1879.

To all whom it may concern:

Be it known that I, JOHN R. WILLIAMS, of Johnstown, in the county of Cambria and State of Pennsylvania, have invented a new and 5 useful Improvement in Machines for Trimming Horseshoe-Banks, of which the following is a specification.

My invention relates to a machine for trimming off the protuberances formed on the 10 edge of a horseshoe-blank by the act of punching nail-creases therein.

The improved machine is constructed with a crown-saw revolved by a horizontal shaft, in front of which works a vertical slide adapted 15 to receive the blank and carry it upward across the edge of the saw, and a vertical guide block or standard, horizontally adjustable toward or from the front of the saw, and adapted to receive the vertically-moving slide.

20 In order that my invention may be fully understood, I will proceed to describe it with reference to the accompanying drawings, in which—

Figure 1 is a plan of the machine. Fig. 2 is 25 a side view of the same. Fig. 3 is a front view. Fig. 4 is a vertical section of the front portion of the machine on the line 4 4, Fig. 3.

A represents a horizontal shaft, running in bearings on a bed or frame, B, and carrying an 30 annular or crown saw, C. Mounted on the same bed B is a vertical guide block or standard, D, adjusted horizontally toward or from the front of the saw by set-screws E. A slide, F, works vertically on the guiding-standard 35 D, being raised and lowered by means of a horizontal hand or foot lever, I, the inner end of which is connected by a rod, J, with the slide F. The slide F is constructed with a pocket, f, forming a seat to receive a horseshoe-blank, 40 which fits therein, as shown at G, in such position as to bring the protuberances g, which are produced by punching the nail-creases g', just within the vertical plane of the extremities of the saw-teeth, the necessarily accurate 45 adjustment of the guiding-standard D to se-

cure this result being provided by the set-screws E. f' represents a notch in the slide, to receive the lower bit of the tongs used in setting the blank in the slide.

A special slide is preferably used for each 50 style or size of horseshoe-blank, with a seat or pocket in which the particular blank will fit. If preferred, the slide may be made in two parts, the pocket or blank seat being contained in a removable cap to facilitate changing from 55 one size or shape of blank to another; or the blank may be clamped on the top of the slide without a pocket or seat to receive it, so that one slide may be made to do for blanks of any size.

In operation, the workman takes a blank 60 from a creasing-machine—such, for example, as I have described in another application for Letters Patent—and without shifting his tongs therefrom places it in the seat prepared for it 65 in the slide F, the lower bit of the tongs resting in the notch f', as before stated. By a downward pressure of his foot or hand on the lever I, he then elevates the slide F, and as the blank is carried across the edge of the annular saw at its upper part the protuberances 70 g are trimmed off smoothly to the proper surface of the edge of the blank.

Having thus described my invention, the 75 following is what I claim as new therein and desire to secure by Letters Patent:

1. A machine constructed, substantially as herein described, with a crown-saw, C, and a slide, F, adapted to receive a horseshoe-blank and carry it across the edge of the saw by a 80 transverse movement.

2. The combination, with the saw C, of the horizontally-adjustable block or standard D and the vertically-moving slide F, as and for the purpose described.

JOHN R. WILLIAMS.
